Primary Examiner — Cynthia R Underwood

(57) **CLAIM**

The ornamental design for a zipline trolley, as shown and described.

DESCRIPTION

FIG. 1 is a perspective view of an exemplary zipline trolley according to the present disclosure;
FIG. 2 is a front view of the zipline trolley of FIG. 1;
FIG. 3 is a rear view of the zipline trolley of FIG. 1;
FIG. 4 is a right side view of the zipline trolley of FIG. 1;
FIG. 5 is a left side view of the zipline trolley of FIG. 1;
FIG. 6 is a top view of the zipline trolley of FIG. 1; and,
FIG. 7 is a bottom view of the zipline trolley of FIG. 1.
The broken lines represent environment that form no part of the claim.
